New Jersey

Application September 1, 1933, Serial No. 687,834
In Great Britain September 29, 1932

4 Claims. (Cl. 91—46)

This invention relates to apparatus for subjecting pervious materials to impregnating liquids, and is herein described chiefly with regard to tempering leather soles, although apparatus of the type herein described has utility also for impregnating leather and other pervious materials with liquids having effects other than tempering, for example, a water-proofing effect.

It has been found in practice that impregnation of leather submerged in a liquid can be effected much more rapidly, and with more satisfactory results, when the liquid is put under super-atmospheric pressure than when it remains at atmospheric pressure, and that if a suitably high pressure of the liquid is developed during the period of treatment it avoids the necessity of leaving the work in a wet pack for several hours after its removal from the bath. By way of explanation, it is supposed that the air occluded in the pores of leather resists the entrance of liquid, and that if the liquid remains at atmospheric pressure during the period of treatment hours of capillary action are necessary to bring about thorough penetration of the leather by the liquid, whereas, if the pressure of the liquid is high during the period of submersion the penetration is correspondingly rapid and even. Moreover, when leather soles are tempered with water under high pressure, and not left in the water more than a very few minutes the soles do not become sodden or stained, as they do in many cases when subjected to prolonged treatment with water at atmospheric pressure.

With the foregoing conditions in view, an object of the present invention is to provide improved apparatus by which articles of leather or other pervious material may be quickly impregnated under super-atmospheric pressures.

A novel feature of the invention consists in an impregnating apparatus comprising a pressure-sustaining receptacle having a work-receiving mouth, a pressure-sustaining closure movable into and out of the mouth, a work-carrier suspended from and rigidly related to the closure, and means arranged to develop pressure of an impregnating liquid confined in the receptacle. Since the work-carrier is supported by the closure, it does not require any individual handling to place it in the receptacle or to remove it therefrom, the operations of applying the closure and removing it from the receptacle being thus utilized to do double duty. Preferably, to facilitate placing the closure in the mouth of the receptacle, the work-carrier and the receptacle are provided with cooperative guiding surfaces by which the closure

is maintained in alignment with the mouth to insure the desired guidance of the closure.

The invention also comprises other features of improvement hereinafter described.

Referring to the drawings,

Fig. 1 is an elevation of an improved apparatus with which the herein-described method may be practiced;

Fig. 2 is a plan view of that portion of the apparatus below line II—II in Fig. 1;

Fig. 3 is a plan view of the tempering receptacle with the closure applied thereto;

Fig. 4 is a plan view of the closure included in Fig. 3;

Fig. 5 is a vertical section on a larger scale through an automatic sealing device influenced by super-atmospheric pressure in the tempering receptacle to prevent leakage past the closure therefor;

Fig. 6 is a perspective view of the upper portion of the tempering receptacle provided with one form of means for securing a closure of the type shown in Figs. 1, 3, 4 and 5;

Fig. 7 is a view similar to Fig. 6 but including an alternative form of means for securing the closure shown in Fig. 8; and

Fig. 8 is a perspective view of a closure designed to cooperate with securing means of the type shown in Fig. 7.

The base 1 of the apparatus supports a superposed member 3 rigidly bolted thereto to provide a mounting for a bowl-shaped member 7 and a pedestal 5 both of which are bolted to the member 3. The pedestal 5 provides a mounting for an upstanding tempering or impregnating receptacle 9 which may be cylindrical and may be fixed in operative position by clamping devices 11 secured to the pedestal. The walls of the receptacle 9 are designed to withstand internal hydraulic pressure of more than 1500 pounds per square inch. This receptacle is closed except at its upper end which is provided with a ring 13 secured thereto by bolts 15 capable of withstanding the greatest hydraulic pressure to which the receptacle will be subjected in practice. One purpose of the ring 13 is to provide an interlocking connection with a closure, hereinafter described, to form a modified bayonet-joint. Moreover, the ring 13 is provided with a laterally extending boss 17 to provide anchorage for a stationary post 19 which constitutes a track for a trolley 21 arranged to run up and down thereon to guide the closure.

The trolley 21 has four thin rolls 22, two of which are arranged to run in a groove 23 extending lengthwise of the post and the other two of

which are arranged to run in a similar groove diametrically opposite that first mentioned. An arm 25 formed on the trolley 21 is provided with a vertical bearing in coaxial relation to the receptacle 9, this bearing being occupied by a shaft 27. The closure 29 is affixed to the lower end of the shaft 27, an a cross-bar 49 extending through the upper end of this shaft provides two handles by which the shaft and the closure may 10 be turned about a vertical axis to interlock the closure with the ring 13 when the closure is nested in the ring. The upper end of the shaft 27 carries a hook by which it is suspended from a flexible steel cable 37 provided with a counterweight 15 39 which is preferably slightly heavier than the greatest load that would ever be imposed upon the other end of the cable. The cable passes over sheaves 33 and 35 mounted on a supporting bracket 31 which is affixed to the upper end of the post 20 19.

The body of the closure 29 is cylindrical and of a size to fit closely in the mouth at the upper end of the receptacle 9 with only sufficient clearance to enable it to enter it readily, but is provided with radially projecting segmental ears 41 of suitable proportions to pass through complementary notches between inwardly projecting ears 47 formed on the ring 13. When the ears 41 of the closure 29 are in register with the notches in 30 the ring 13 they may descend into engagement with a flat annular seat 45 provided by an internal flange 43 formed on the ring 13. When so seated the ears 41 lie on the seat 45 and the closure may be turned about its axis far enough to place the 35 two sets of ears in interlocked relation. Such turning of the closure may be effected manually by means of the cross-bar 49.

When the closure is supported by the cable 37 and the counterweight 39, it supports the trolley 40 21, but the bearing in the arm 25 through which the shaft 27 extends is preferably shorter than the distance between the closure and the cross-bar 49 to provide for a short relative axial movement of the shaft and the bearing element. This 45 feature of construction may be utilized to maintain the ears 41 in register with the notches in the ring 13 when the closure is raised, to the end that the operator will be relieved from the necessity of turning the closure incidentally to depressing it to its seat 45 (Fig. 6). For example, as shown in Figs. 1 and 4, the closure 29 is provided on its upper surface with an upstanding tooth 51 having oppositely inclined camming surfaces. This tooth is arranged to enter correspondingly shaped notches 53 and 55 formed in 50 the lower end of the bearing provided by the arm 25. When the ears 41 are in register with the notches in the ring 13, the tooth 51 occupies the notch 55, the weight of the trolley 21 being then 55 effective to prevent accidental turning of the closure, but a moderate turning force applied to the closure by means of the cross-bar 49 will be sufficient to shift the tooth from the notch 55 to the notch 53. As the closure is turned in this 60 manner, the inclined face on the left-hand side of the tooth 51 will operate with a camming effect on the arm 25 to raise the trolley 21, but when the tooth is brought into register with the notch 53 the trolley will descend to its former level and 65 thus prevent accidental turning in the opposite direction. A similar camming effect is produced by the other inclined face of the tooth 51 when the turning force is applied in the direction necessary to disengage the ears 41 of the closure from 70 the ears 47 of the locking ring.

To insure a non-leaking joint between the receptacle 9 and the closure 29 when these parts are interlocked, the receptacle is provided with a sealing device that will be operated automatically by the hydraulic pressure developed in the receptacle. A device for this purpose may embody the construction shown in Fig. 5. The upper end of the receptacle 9 is provided with a counterbore 56 to receive a metal ring 59 and a molded gasket 57 of comparatively soft and expandable material 10 such as leather or rubber. These elements are placed in the counterbore before the locking ring 13 is bolted to the receptacle, but when the locking ring is assembled therewith it confines the gasket 57 and the ring 59 against vertical displacement. The upper portion of the ring 59 is comparatively thin and is straddled by the skirts of the gasket 57 which is U-shaped in cross-section and arranged to place the fold at the top. At suitable intervals, ducts 61 are formed in the 20 metal ring 59 leading from the chamber in the receptacle 9 to the upper edge of this ring, and these ducts are intersected by radially extending ducts 63 that lie in the channel of the gasket. In operation, when super-atmospheric pressure is 25 developed in the receptacle 9 air and liquid are forced under pressure through the ducts 61 and 63 into the channel of the gasket 57 which is thereby distended radially before a balance of pressure can be set up against the sealing surfaces of the 30 skirts of the gasket with the result that the inner skirt is seated tightly against the closure, while the external skirt is likewise seated firmly against the surrounding surface of the counterbore in the receptacle. As the hydraulic pressure increases, it causes a corresponding increase of the pressure of the skirts of the gasket against the confining surfaces of the closure and the counterbore and thus prevents leakage of the liquid 35 through the locking ring 13. 40

Fig. 7 illustrates a locking ring 67 corresponding to the locking ring 13 but embodying ears of a different form designed to cooperate with a closure of the type shown in Fig. 8. In the latter figure, the closure indicated at 79 is provided 45 with segmental ears 65, the ends of which have inclined surfaces which operate with a camming effect in consequence of rotational movement of the closure. Likewise, the ears 69 of the locking ring 67 have correspondingly inclined camming 50 surfaces at their ends, and the flat segmental seats 71 on which the ears 65 of the closure rest are provided with inclined camming projections 73, each forming a continuation of the inclined 55 surface at one end of an ear 69. When the operator turns the closure in a counterclockwise direction to release it from the locking ring 67, the ears 65 ride up first on the inclined projections 73 and thereafter on the inclined ends of the ears 69 to start the closure on its upward 60 travel which, when release is effected, will be completed by the counterweight 39.

To discharge any liquid that may accumulate in the locking ring 13 above the flat seat 45, the ring may be bored radially to provide an outlet 65 port and this port may be tapped to receive a screw-threaded pipe or nozzle 75 through which the accumulated water will be directed into the bowl-shaped member 7. In like manner, if a locking ring of the type shown in Fig. 7 is used 70 it may be provided with one or more discharge nozzles 77.

Figs. 1 and 2 illustrate pumping apparatus by which a tempering liquid may be forced into the tempering receptacle 9 and by which any 75

suitable or desired hydraulic pressure may be developed in the receptacle. The pumping apparatus may be of any preferred or well-known commercial construction, but for reasons hereinafter explained it is desirable to provide two pumps, one of relatively large capacity for filling the receptacle 9 quickly and for developing a moderate pressure therein, and the other of smaller capacity for developing supplemental pressure. As shown, two such pumps are arranged in a storage tank 79 bolted to the base 1. This tank may be provided with a hinged cover 197 adapted to be opened for the purpose of pouring tempering fluid into the tank. The pump of larger capacity comprises a cylinder 81 (Fig. 2) and a piston 83, the diameter of which may be about two inches. A check-valve 85 admits tempering fluid into the cylinder 81 from the tank 79 while a corresponding check-valve 87 permits the fluid to be expelled from the cylinder into a manifold 88 from which the liquid flows through a pipe 91 into the lower portion of the tempering receptacle 9. A lever 89 arranged to be operated manually is operatively connected to the piston 83.

In like manner, a high-pressure cylinder 93 of smaller capacity is provided with a piston 95, their diameters being approximately $\frac{3}{4}$ of an inch. The tempering liquid is admitted into the cylinder 93 from the tank 79 through a check-valve 97 and is expelled from this cylinder into the manifold 88 through a delivery port in which a check-valve 99 is installed. A lever 101 is operatively connected to the piston 95 and intended to be operated manually. To prevent the development of excessive pressure, the high-pressure cylinder 93 may be provided with a relief valve 103 controlled by the force of gravity through the agency of a lever and a weight adjustably arranged thereon. The weight may be shifted to regulate the maximum pressure that may be developed before relief is afforded. If desired, a pressure indicator 105 may be installed at any suitable point, for example in the manifold 88, where it will indicate the pressure developed in the receptacle 9.

To provide for venting the receptacle 9 so that it may be filled with tempering liquid after the closure has been sealed, a pressure-sustaining valve 111 is screwed into the receptacle at a level only slightly below that of the lower end of the closure. A pipe 109 extends downwardly from this valve into the bowl-shaped member 7. In operation, when the work to be tempered has been placed in the receptacle and when the closure has been locked in operative position, the valve 111 will be open to release the air from the receptacle. The operator will thereupon move the lever 89 back and forth to operate the low-pressure piston 83 by which the tempering liquid in the tank 79 will be rapidly forced into the receptacle 9. In due course, some tempering liquid will escape from the receptacle 9 through the pipe 109 and thereby indicate the fact that nearly if not quite all the air in the receptacle has been expelled by liquid. Now the operator will close the valve 111 and may develop a considerable pressure in the receptacle by further operation of the lever 89. If pressure greater than that easily obtainable with the lever 89 is desired, the operator may operate the high-pressure pump by means of the lever 101.

The tempering receptacle 9 may also be provided with a pressure-sustaining valve 113 preferably situated at its lower end to provide for

draining and flushing the receptacle whenever desired, but while the apparatus is in use this valve will remain closed. If desired, the valve 113 may be provided with a nozzle arranged to discharge the liquid into the bowl-shaped member 7 and the bowl may be provided with a drain pipe 115 to conduct the accumulated liquid from the bowl-shaped member to any convenient point of discharge.

To expedite the introduction of the work into the receptacle 9 and its removal therefrom, a rigid work-carrier 117 is suspended from the closure 29. The carrier may be a sheet-metal shell preferably made of some metal that will not be affected by the tempering liquid. Since water will commonly be the liquid used for tempering, the work-carrier may be made of sheet brass and will have an opening in its upper portion to receive the work to be tempered. As represented in Fig. 1, the work-carrier has a bottom wall in which perforations (see dotted lines) are formed to admit and drain the tempering liquid.

For the sake of illustrating the work-carrier as clearly as possible in Fig. 1, the vertically movable assemblage of which it forms a part is shown at 25 a position higher than that actually necessary to facilitate the insertion of the work into the carrier. Preferably, the post 19 will be provided with a stop such as a projecting pin 119 adapted to arrest the upward movement of the trolley 30 at a point that will leave the lower portion of the work-carrier in the mouth of the receptacle 9 but still permit the work-receiving opening in the carrier to rise above the top of the locking ring 13. It is to be understood, therefore, that for the 35 sake of illustration the pin 119 has been withdrawn to permit the trolley 21 to rise to the position shown.

The work-carrier 117 is rigidly related to the closure 29 and is cylindrical to conform to the 40 internal surface of the receptacle 9. Consequentially this surface and the external surface of the work-carrier cooperate with each other to maintain the closure in alignment with the mouth of the receptacle, in which respect their control is 45 superior to that of the trolley 21 which might swing slightly about the post 19.

Since a procedure for pumping tempering liquid into the receptacle 9 has already been described, further description of the operation may be restricted to the procedure of removing the work from the receptacle when the tempering treatment has been completed. Assuming that it is desired to remove the work from the receptacle after a suitable period of treatment, the operator 55 will first open the relief valve 111 to relieve the pressure in the receptacle. A small quantity of tempering liquid may be discharged through the pipe 109 when the valve 111 is opened but the liquid will not fall below the level of this valve 60 under such conditions. When the pressure in the receptacle is entirely relieved the gasket 63 (Fig. 5) will become relaxed so that the closure 29 may be readily withdrawn. The operator may now turn the handle 49 to disengage the locking ears 65 of the closure from those of the locking ring 13. The closure and the work-carrier are now free to be raised and if, because of the presence of liquid in the receptacle 9 and in the work-carrier, or because of a clinging of the sealing gasket to 70 the closure, the latter does not respond immediately to the influence of the counterweight 39 the operator may assist the counterweight by applying a slight upward force to the handle 49.

The length of time and the degree of hydraulic 75

pressure required to insure the most satisfactory tempering treatment will be governed to a great extent, if not entirely, according to the density of the work and may also be governed to some extent by the character of the tempering liquid if a liquid other than water is used or if some other tempering substance is combined with water. Nevertheless, it may be stated as a general rule that these factors should be regulated to cause the tempering liquid to penetrate each work-piece nearly if not quite to the heart of the stock, but the tempering treatment should not be continued so long as to render the stock sodden. Experience with leather of different qualities will soon demonstrate how best to regulate the pressure and the duration of treatment. It has been found that leather soles of usual good quality will be satisfactorily tempered under a pressure of 1500 pounds per square inch without prolonging the duration of treatment after that pressure has been attained with the apparatus described. Consequently, as soon as the operator has developed a pressure of this degree, he may immediately open the valve 111, unlock the closure and withdraw the work-carrier from the tempering receptacle. Under such conditions, the entire operation from the time of placing the untempered work in the carrier 117 until the removal of the tempered work therefrom need not require more than three minutes. It has also been found that the leather does not become stained when the tempering liquid is forced under high pressure into the interstices of the stock and the treatment is limited to a short period of time. If the leather to be treated is cut from exceptionally hard, hammered bends, satisfactory treatment may require from two to five minutes at a pressure of 1500 pounds per square inch of the tempering liquid. On the other hand, if the leather is softer and more permeable a pressure of 1500 pounds per square inch would not be necessary or desirable because it would be likely to render the leather sodden almost immediately. Therefore, in tempering such leather it is preferable to operate with pressures ranging from 250 pounds to 400 pounds per square inch which may readily be developed with the low-pressure pump operated by the lever 89. Under such conditions, when the gage 105 indicates that the desired pressure has been developed the operator will immediately open the valve 111 and withdraw the work from the tempering receptacle. It is to be understood that the described apparatus and method of procedure may also be used for purposes other than tempering leather.

For example, they may be used to impregnate leather and other substances with oleaginous water-proofing liquid with corresponding saving of time and thoroughness of treatment.

Having described our invention, what we claim is new and desire to secure by Letters Patent of the United States is:

1. An impregnating apparatus comprising a pressure-sustaining receptacle having a work-receiving mouth, a pressure-sustaining closure movable into and out of said mouth, a rigid work-carrier suspended from and rigidly related to said closure, the receptacle and the work-carrier having cooperative guiding surfaces by which the closure is maintained in alignment with said mouth, and means arranged to develop pressure of an impregnating liquid confined in the receptacle.

2. An impregnating apparatus comprising a pressure-sustaining receptacle having a work-receiving mouth, a pressure-sustaining closure movable into and out of said mouth, means arranged outside the receptacle to guide the closure into said mouth, a work-carrier suspended from said closure, the receptacle and the work-carrier having cooperative guiding surfaces, and means arranged to develop pressure of an impregnating liquid confined in said receptacle.

3. An impregnating apparatus comprising a pressure-sustaining receptacle having a work-receiving mouth at the top, a pressure-sustaining closure for said mouth, said closure and the receptacle having cooperative parts arranged to be interlocked in consequence of turning the closure about a vertical axis, a vertically movable guide supported by said closure, a track for said guide, and cooperative camming parts on said closure and said guide for normally maintaining the closure in a certain angular position with regard to turning about said axis, said camming parts being rendered effective by the weight of the guide and the latter being arranged to yield upwardly to a moderate turning force applied to the closure.

4. An impregnating apparatus comprising a pressure-sustaining receptacle having a work-receiving mouth at the top, a pressure-sustaining closure for said mouth, said closure and the receptacle having cooperative parts arranged to be interlocked in consequence of turning the closure about a vertical axis, a counterweighted suspension line from which said closure is suspended, means for guiding the closure in a vertical path, and a work-carrier suspended from said closure.
